UNITED STATES PATENT OFFICE

2,140,454

TWO-STROKE INTERNAL COMBUSTION ENGINE

Werner Howald, Zurich, Switzerland

Application October 29, 1936, Serial No. 108,291
In Switzerland November 12, 1935

12 Claims. (Cl. 123—81)

The invention relates to a two-stroke internal combustion engine wherein the sleeve valve carries out a movement parallel to its axis combined with an oscillating movement about its axis in such a way that the absolute path of each point of the sleeve valve surface constitutes a closed curve.

The invention resides in the fact that the rotating movement of a crank shaft or of an eccentric is transmitted to the sleeve valve by a connecting rod in such a manner that the component of the movement parallel to the axis of the cylinder of each part of the surface of the sleeve valve circumscribing as above mentioned a closed curve, has at each working stroke, during the time the piston has attained its highest velocity, the same direction as the direction of movement of the piston itself. Furthermore, the sleeve valve shows the greater acceleration during the time that the sleeve valve controls the working chamber than during the time that the working chamber is completely closed and the compression and combustion pressure attains its maximum value.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, and then be particularly pointed out in the appended claims, reference being had to the accompanying drawings, in which:

Fig. 1 is a diagrammatic vertical section of an engine embodying the invention.

Fig. 2 is a detail cross-section of the same on the line 2—2 of Fig. 1.

Figs. 3 and 4 show the path-time and control diagrams.

Fig. 5 is a vertical section of a portion of a radial cylinder engine embodying the invention.

Fig. 6 is a detail section on the line 6—6 of Fig. 5.

Fig. 7 is an enlarged detail section on the line 7—7 of Fig. 5.

Fig. 8 is an enlarged elevation and part section of the lower portion of Fig. 5.

The drawings show the cylinder 1, sleeve valve 2 with driving pin 2', cylinder cover 3, working piston 4, connecting rod 5, crank shaft 6, two sleeve valve driving crank shafts 7, eccentric 7', crank pin 7'', connecting rod 8, pivot 9, eccentric sheave 10, driving beam 11 with slide

guide 11' for the eccentric sheave, bearing 13, and gudgeon 14.

In the sleeve valve drive according to the invention shown in Figs. 1 and 2 the driving shaft 7 rotates with the same speed as the crank shaft 6, and the horizontal component of the curve of movement C is transmitted from an eccentric 7' rotating in the same direction with the crank pin 7'' of the sleeve valve driving shafts 7, and having no, or almost no, angular displacement 5 relatively to the crank pin 7'', by means of the eccentric sheave 10 to the slide guide 11' of the driving beam 11, while the vertical component is transmitted from the crank pin 7'' by means of the connecting rod 8 to the pivot 9 mounted 10 in the driving beam 11, and partaking of the horizontal movement positively with this. This pivot 9 therefore does not move along a vertical line but along a curve corresponding with the curve of movement C. This fact, as the pivot 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630

In Fig. 1 (as shown at the right hand side) exhaust A is effected at the outer end of the working chamber, while the admission B of scavenging air and the admission B' of the supercharging air or of the charging mixture, takes place at the inner end of the working chamber.

The abscissa in Figs. 3 and 4 corresponds to one revolution of the crank shaft; the units are degrees or time units. For each position of the crank shaft the corresponding position of the fixed control edges A_o and A_u, of the outlet A, B_o and B_u, of the scavenging slots B, B'_o, and B'_u, of the supercharging slots B', of the moving control edges S_o and S_u, of the sleeve valve, and of the control edge 4_o of the piston are shown. The arrows indicate the sense of rotation of the crank shaft, and the corresponding movements of the piston and of the sleeve valve. Above the path-time diagram 4, are shown the corresponding velocity-time diagram and the acceleration-time diagram of the sleeve valve. The two last-mentioned diagrams show the points of highest velocity W, and of the highest acceleration P_o and P_u at the higher and the lower dead point of the sleeve valve, and the two maxima of the acceleration P on each side of the higher dead point. The phase difference between the movement of the piston and of the sleeve valve is 55

marked α , and is equal to the distance between the two horizontal tangents to the path-time diagrams of the piston and the sleeve valve respectively at the points of maximum amplitude. 5 The phase difference does not impede so that the movement of the piston and of the sleeve valve has the same direction during the time of maximum velocity of the piston at each stroke. As the Figs. 1, 3 and 4 show, the sleeve valve 10 controls the slots during the time of the highest acceleration P_u , and the difference between the maximum acceleration of the two dead zones of the oscillating sleeve valve has been made possible by making the ratio of crank radius to length of 15 the connecting rod as great as possible. The two dead zones with different maximum accelerations P_u and P_o in the dead points, are separated from each other by the two zones of maximum velocity W . The above-mentioned ratio can be made 20 equal to, smaller, or greater than 1, by imparting to the beam 11, besides its oscillating movement parallel to the cylinder axis, also a movement at a right angle to the mentioned axis. This is the reason for the movements shown in Figs. 1 and 4 25 which are particularly favorable for controlling. The diagram according to Fig. 4 differs from the diagram 3, only in that the section b representing the scavenging time, is made smaller in order to increase b' representing the scavenging time 30 cross section.

The ordinates of the vertically shaded areas a , b and b' , show the course of the internal slot heights which multiplied by the corresponding slot widths, give the cross-sectional areas of the 35 exhaust A into the atmosphere or into an exhaust turbine, preferably a free exhaust turbine, of the inlet B for the scavenging air, and of the inlet B' for the supercharging air or charging mixture. By reversing the direction of rotation of the crank 40 shaft and of the sleeve valve driving shaft, or, what amounts to the same thing, by turning the sleeve valve driving shaft relatively to the crank shaft corresponding to an equal or almost equally large lag, the exhaust A instead of being effected 45 unseparated at the outer end of the working chamber, may be effected at the inner end of the working chamber separately into exhaust A³, to the pre-exhaust turbine, and exhaust A³, into 50 the atmosphere or into the exhaust of the pre-exhaust turbine or into the subsequent exhaust and scavenging gas turbine, while the inlet B of the scavenging air and the inlet B' of the supercharging air or of the supercharging mixture, instead of being effected separately at the inner 55 end of the working chamber is effected unseparately at the outer end of the working chamber through the inlet B², as indicated at the left-hand side of Fig. 1.

In order to avoid the necessity of providing two 60 separate sleeve valve driving shafts 7 for each sleeve valve, the arrangement of the driving shafts 7 is such that two driving beams 11 are coupled to one driving shaft 7 (Figs. 5-8), in such a manner that for one driving beam 11 the horizontal component of the movement curve is produced by means of the eccentric 7', and the eccentric sheave 10 and the vertical component by 65 means of the crank pin 7' and the connecting rod 9, while for the other driving beam 11 only 70 the vertical component is produced by means of the second crank gear, this movement being necessary for the parallel guiding of the driving beam 11. By the arrangement of the sleeve valve driving shafts in the corners of the crank casing, 75 the bores for the reception of the bearing bushes

no longer lie directly in the line of power transmission from the working cylinder to the working crank shaft bearing, which is of considerable importance for the durability of the highly stressed crank casing. The length of the connecting rods of the drive of the vertical reciprocating movement of the sleeve valve is so short that connecting rods can no longer be used, but the diameter of the running surface of the pivot 5 9 (Figs. 1, 2), must be made so large that the 10 crank pin comes to lie within the running surface of the pivot 9, the connecting rod thus becoming a round disc, or the running track is divided into two running track sectors, symmetrical to the connecting line between the 15 centers of the crank pin and the pivot center, one of the sectors 9', that surrounding the crank pin, of the same radius as the connecting disc, the other 9'' of smaller radius.

As the running surfaces 9' and 9'' of the connecting discs 8, and also the corresponding running surfaces of the driving beams 11 about the center 9 are constructed spherically, a uniform supporting of the running surfaces both between the connecting discs 8 and the driving beams 11 20 is always obtained, and the connecting discs 8 and the crank pins of the sleeve valve driving shaft 7 as the connecting discs 8 adjust themselves automatically, in the case of inaccuracies or slight deformations of the crank pin in consequence of the spherical running tracks 9' and 9''. 25 As the running track of the slide guide 11', as also that corresponding with the eccentric sheave 10, are constructed cylindrically in a plane at right angles to the plane of movement 30 of the eccentric sheave 10 on the slide guide 11' from the common center 7'', there is obtained the result that the running surfaces 10' and 11'', which in addition to the horizontally acting mass 35 inertia forces in consequence of the oscillating movement, also have to take up the normal pressures of the connecting discs resulting from the vertical valve movement, always support uniformly over the entire width; in addition, the driving beam is prevented from turning about 40 the center 9 of the spherical running surfaces 9' and 9''. The transmission of the movement 45 from the driving beam 11 to the pivot 2' of the sleeve valve 2, is effected through the bearing 13 which is secured to the driving beam 11 by means 50 of two set screws, and is centered by cylindrical centering from the center of the gudgeon 14, and by the gudgeon 14 is mounted spherically in the bearing casing 13. In spite of the offsetting of the driving beam 11, no tilting moments act on 55 this, as the centers of the two connecting discs 8 and of the gudgeon 14, are located in one plane and the vertical forces are balanced. The torque, resulting from the normal pressure of the connecting disc 8 and the distance 1 and 1' of the 60 central planes of the connecting discs 8 and of the eccentric 7, is taken up by the spherical running surfaces between the driving beam 11 and the connecting discs 8, and transmitted to the connecting discs 8, which in turn are prevented 65 from axial movement by the disc 15 and the screw 16.

From the foregoing description, taken in connection with the accompanying drawings, it is thought that the construction, operation and advantages of the invention will be clear to those skilled in the art.

I claim:

1. In a sleeve valve two-stroke internal combustion engine which includes a cylinder, a sleeve 75

valve, a piston, a crank shaft and a connecting rod between said crank shaft and said piston; means to operate said valve, which means includes two additional crank shafts located in a plane substantially normal to the axis of the piston, a driving beam, connecting rods connecting the cranks of said two additional crank shafts to said beam, said beam lying approximately parallel to said plane, and a driving pivot connecting said beam to said sleeve valve, a slotted guide carried by said beam and an eccentric sheave movable in said guide, and an eccentric on one of said two additional crank shafts and carrying said eccentric sheave.

15 2. In a sleeve valve two-stroke internal combustion engine which includes a cylinder, a sleeve valve, a piston, a crank shaft and a connecting rod between said crank shaft and said piston; means to operate said valve, which means includes two additional crank shafts, a driving beam, a driving pivot connecting said beam to said valve, connecting rods connecting said beam to the cranks of said additional crank shafts for raising and lowering said beam, and other means 20 connecting one of said cranks with said beam for moving said beam laterally while it is being raised and lowered.

25 3. In a sleeve valve two-stroke internal combustion engine which includes a cylinder, a sleeve valve, a piston, a crank shaft and a connecting rod between said crank shaft and said piston; means to operate said valve, which means includes two additional crank shafts, a driving beam, a driving pivot connecting said beam to said valve, connecting rods connecting said beam to the cranks of said additional crank shafts for raising and lowering said beam, and other means 30 connecting one of said cranks with said beam for moving said beam laterally while it is being raised and lowered, said cranks and last-named connecting rods and said other means being so positioned and proportioned that on a path-time control diagram of the engine the zone of movement of the valve during the control of the operative area shows greater acceleration than during that period during which the pressures of 35 compression and combustion attain their maximum values in completely closed operative spaces.

40 4. In a sleeve valve two-stroke internal combustion engine which includes a cylinder, a sleeve valve, a piston, a crank shaft, and a connecting rod between said crank shaft and said piston; means to operate said valve, which means includes two additional crank mechanisms, a driving beam, a driving pivot connecting said beam with said valve, said additional crank mechanisms including means cooperatively connected to said driving beam by virtue of which the component of movement of said driving beam at 45 right angles to the axis of the valve is effected by one of said additional crank mechanisms and the component of movement parallel to the axis of said valve is effected by the other additional crank mechanism, one of said additional crank mechanisms also including means by virtue of which the movement of the valve during the control of the operative area accelerates more 50 greatly than during that period at which the pressures of compression and combustion attain their maximum values.

55 5. In a sleeve valve two-stroke internal combustion engine which includes a cylinder, a sleeve valve, a piston, a crank shaft and a connecting rod between said crank shaft and said piston; means to operate said valve, which means in-

cludes two additional crank shafts located in a plane substantially normal to the axis of the piston, a driving beam, connecting rods connecting the cranks of said two additional crank shafts to said beam, said beam lying approximately parallel to said plane, and a driving pivot connecting said beam to said sleeve valve, a slotted guide carried by said beam and an eccentric sheave movable in said guide, and an eccentric on one of said two additional crank shafts and carrying said eccentric sheave, said eccentric guide and said eccentric sheave having concave and convex abutting faces respectively.

60 6. In a sleeve valve two-stroke internal combustion engine which includes a cylinder, a sleeve valve, a piston, a crank shaft and a connecting rod between said crank shaft and said piston; means to operate said valve, which means includes two additional crank shafts located in a plane substantially normal to the axis of the piston, a driving beam, connecting rods connecting the cranks of said two additional crank shafts to said beam, said beam lying approximately parallel to said plane, a driving pivot connecting said beam to said sleeve valve, a slotted guide carried by said beam and an eccentric sheave movable in said guide, an eccentric on one of said two additional crank shafts and carrying said eccentric sheave, and means to confine said beam to movement in one plane.

65 7. In a sleeve valve two-stroke internal combustion engine which includes a cylinder, a sleeve valve, a piston, a crank shaft and a connecting rod between said crank shaft and said piston, means to operate said valve in such a manner that the sleeve valve moves parallel to its axis and around its axis, the operating means including two eccentric rotating pins, one of said pins having a larger eccentricity than the other one, a driving beam, a driving pivot connecting said beam to said valve, a connecting rod connecting said beam to the rotating pin with the larger eccentricity and producing substantially the movement of the sleeve valve parallel to its axis.

70 8. In a sleeve valve two-stroke internal combustion engine which includes a cylinder, a sleeve valve, a piston, a crank shaft and a connecting rod between said crank shaft and said piston, means to operate said valve in such a manner that the sleeve valve moves parallel to its axis and around its axis, the operating means including two eccentric rotating pins, one of said pins having a larger eccentricity than the other one, a driving beam, a driving pivot connecting said beam to said valve, a connecting rod connecting said beam to the rotating pin with the larger eccentricity and producing substantially the movement of the sleeve valve parallel to its axis, the driving pin with the smaller eccentricity being connected to the beam and producing substantially the movement of the sleeve valve around its axis.

75 9. In a sleeve valve two-stroke internal combustion engine which includes a cylinder, a sleeve valve, a piston, a crank shaft and a connecting rod between said crank shaft and said piston, means to operate said valve in such a way that the sleeve valve moves parallel to its axis and around its axis, the operating means including two eccentric rotating pins, one of said pins having a larger eccentricity than the other one, a driving beam, a driving pivot connecting said beam to said valve, a connecting rod connecting said beam to the rotating pin with the larger

- eccentricity and producing substantially the movement of the sleeve valve parallel to its axis, the driving pin with the smaller eccentricity being connected to the beam by a slide running on this pin and in a track of the beam and producing substantially the movement of the sleeve valve around its axis.
10. In a sleeve valve two-stroke internal combustion engine which includes a cylinder, a sleeve valve, a piston, a crank shaft and a connecting rod between said crank shaft and said piston, means to operate said valve in such a way that the sleeve valve moves parallel to its axis and around its axis, the operating means including two eccentric rotating pins, one of said pins having a larger eccentricity than the other one, a driving beam, a driving pivot connecting said beam to said valve, a connecting rod connecting said beam to the rotating pin with the larger eccentricity and producing substantially the movement of the sleeve valve parallel to its axis, the driving pin with the smaller eccentricity being connected to the beam by a slide running on this pin and in a track of the beam and producing substantially the movement of the sleeve valve around its axis, the connecting rod having a spherical running surface in the beam, and the slide having a cylindrical running track in the beam.
15. In a sleeve valve two-stroke internal combustion engine which includes a cylinder, a sleeve valve, a piston, a crank shaft and a connecting rod between said crank shaft and said piston, means to operate said valve in such a way that the sleeve valve moves parallel to its axis and around its axis, the operating means including two eccentric rotating pins one of these pins having a larger eccentricity than the other one, a driving beam, a driving pivot connecting said beam to said valve, a connecting rod connecting said beam to the rotating pin with the larger eccentricity and producing substantially the movement of the sleeve valve parallel to its axis, the two driving pins being arranged side by side on the same driving shaft.
20. In a sleeve valve two-stroke internal combustion engine which includes a cylinder, a sleeve valve, a piston, a crank shaft and a connecting rod between said crank shaft and said piston, means to operate said valve in such a way that the sleeve valve moves parallel to its axis and around its axis, the operating means including two eccentric rotating pins one of these pins having a larger eccentricity than the other one, a driving beam, a driving pivot connecting said beam to said valve, a connecting rod connecting said beam to the rotating pin with the larger eccentricity and producing substantially the movement of the sleeve valve parallel to its axis, the effective length of the connecting rod being about as large as the eccentricity of the driving pin.
25. In a sleeve valve two-stroke internal combustion engine which includes a cylinder, a sleeve valve, a piston, a crank shaft and a connecting rod between said crank shaft and said piston, means to operate said valve in such a way that the sleeve valve moves parallel to its axis and around its axis, the operating means including two eccentric rotating pins one of these pins having a larger eccentricity than the other one, a driving beam, a driving pivot connecting said beam to said valve, a connecting rod connecting said beam to the rotating pin with the larger eccentricity and producing substantially the movement of the sleeve valve parallel to its axis, the effective length of the connecting rod being about as large as the eccentricity of the driving pin.

rod between said crank shaft and said piston, means to operate said valve in such a way that the sleeve valve moves parallel to its axis and around its axis, the operating means including two eccentric rotating pins one of these pins having a larger eccentricity than the other one, a driving beam, a driving pivot connecting said beam to said valve, a connecting rod connecting said beam to the rotating pin with the larger eccentricity and producing substantially the movement of the sleeve valve parallel to its axis, the two driving pins being arranged side by side on the same driving shaft.

12. In a sleeve valve two-stroke internal combustion engine which includes a cylinder, a sleeve valve, a piston, a crank shaft and a connecting rod between said crank shaft and said piston, means to operate said valve in such a way that the sleeve valve moves parallel to its axis and around its axis, the operating means including two eccentric rotating pins one of these pins having a larger eccentricity than the other one, a driving beam, a driving pivot connecting said beam to said valve, a connecting rod connecting said beam to the rotating pin with the larger eccentricity and producing substantially the movement of the sleeve valve parallel to its axis, the effective length of the connecting rod being about as large as the eccentricity of the driving pin.

WERNER HOWALD.
